US00D801970S

(12) **United States Design Patent** (10) **Patent No.:** **US D801,970 S**
Sullivan et al. (45) **Date of Patent:** **** Nov. 7, 2017**

(54) **HEAD MOUNTED DISPLAY**(71) Applicant: **Oculus VR, LLC**, Menlo Park, CA
(US)(72) Inventors: **Joseph Patrick Sullivan**, Issaquah, WA
(US); **Yi-yaun Chen**, Seattle, WA (US);
Peter Wesley Bristol, Seattle, WA
(US); **David Michael Pickett**, Seattle,
WA (US); **Enric Vial Roig**, Seattle, WA
(US)(73) Assignee: **Oculus VR, LLC**, Menlo Park, CA
(US)(**) Term: **15 Years**(21) Appl. No.: **29/606,524**(22) Filed: **Jun. 5, 2017****Related U.S. Application Data**

(60) Continuation of application No. 29/575,975, filed on Aug. 30, 2016, now Pat. No. Des. 791,127, which is a division of application No. 29/529,900, filed on Jun. 11, 2015, now Pat. No. Des. 771,625.

CLAIM

The ornamental design for a head mounted display, as shown and described.

DESCRIPTION

FIG. 1 is a front isometric view of a third embodiment of a head mounted display showing the new design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

Any broken lines in the Figures are for illustrative purposes only and form no part of the claimed design.
